CLAIM

The ornamental design for a LED light string, as shown and described.

DESCRIPTION

FIG. 1 is a perspective view of a LED light string showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and

FIG. 8 is an enlarged view of area 8 in FIG. 1;

FIG. 9 is an enlarged view of area 9 in FIG. 4;

FIG. 10 is an enlarged view of area 10 in FIG. 5;

FIG. 11 is an enlarged view of area 11 in FIG. 6; and,

FIG. 12 is an enlarged view of area 12 in FIG. 6.

The dot-dash lines surrounding the enlarged view in FIGS. 1, 4, 5, 6, 8, 9, 10, 11, 12 show the boundaries of the enlarged views and form no part of the claim thereof.

The broken lines in the drawings illustrate portions of the LED light string that form no part of the claimed design.
